UNITED STATES PATENT OFFICE.

EARL H. ROLLINSON, OF LYONS FARMS, NEW JERSEY.

LOUD-SPEAKING-TELEPHONE RECEIVER.

Application filed December 13, 1923. Serial No. 680,324.

In the recent rapid development of radio-
telephony, there has been a tendency to very
materially increase the power of transmis-
sion, and also the power utilized for sound
5 amplification, with the result that the re-
ceiver diaphragm, being usually of very
thin sheet steel or iron, is of insufficient bulk
and thickness to carry the correspondingly
increased magnetic flux without the accom-
panying increase in amplitude of vibration.
10 If made thicker and heavier to withstand
the increased magnetic pull, the attendant
stiffness of the diaphragm will only impair
the clarity of transmission. Since clearness
15 is as essential as loudness in good transmis-
sion, it becomes quite necessary to provide
some means for taking care of the increased
amplitude, due to the increased magnetic
flux in high powered receiving sets, without
20 any damping effect upon the diaphragm.

It is to accomplish the result above indi-
cated that the present improvement was
designed, and it consists in providing a
25 diaphragm of either metallic or non-metallic
material and of very much increased di-
ameter, and mounting at the center thereof
a separate and distinct armature of a di-
ameter corresponding closely to that of the
30 usual standard receiver. This armature
may be what is termed the floating type, or
it may have its periphery supported some-
what after the manner of the usual dia-
phragm. It is, however, an armature and
35 not a diaphragm, and its sole function is to
transmit the successive impulses due to the
undulating magnetic flux in the receiver
magnet system to the true diaphragm.

In the accompanying drawing forming a
part hereof, the improvement is shown as
40 adapted for use in connection with an ampli-
fying horn, and permanently mounted in a
supporting base. However, this method of
mounting is illustrative only, since the re-
ceiver may be provided with the usual de-
45 vices used in forming the well-known head
sets.

Fig. 1 is a section of so much of the re-
ceiver and its supporting base as is neces-
50 sary to understand the improvement.

Fig. 2 is a similar section detached from
the base, and showing the armature as sup-
ported upon the rim of the receiver cup.

Fig. 3 is a detached edge view of the form
55 of connected armature and diaphragm
shown in Fig. 1.

Fig. 4 is an under plan of the same.

Figs. 5 and 6 are views similar to those
of Figs. 3 and 4, but showing the form of
armature used when it is intended to be sup-
ported upon the rim of the receiver cup. 60

The receiver is shown as mounted in a
supporting base 1, which is of molded bakes-
lite or condensite, or it may be of any suit-
able material for the purpose. It is a broad
flat, inverted dish-shaped ring, having a 65
screwthreaded aperture in its upper face, to
receive the extended skirt or flange of the
receiver cap 2, within which the usual
receiver cup 3, with its magnet system 4 is
located, as shown. 70

In order to provide for the enlarged dia-
phragm as hereinafter described, an ex-
tension ring 5 is utilized, said ring being
both externally and internally threaded to
screw into the internally threaded cap flange 75
and to receive the upper threaded portion of
the receiver cup.

The upper part of the cap 2 is provided
with an internally threaded and flanged
aperture 6, into which the thimble 7 of an
amplifying horn may be screwed. Within
the cap 2, and between its lower face and
the margin of the ring 5 are two gaskets 8,
9, between which a margin of the diaphragm
10 is held, the ring being firmly screwed up 85
so as to firmly clamp the diaphragm within
the cap. Suspended from the center of the
diaphragm 10 to which it is secured by the
coupling and rivet 11, is the disk armature
12, which is made much thicker and heavier 90
than the usual diaphragm, in order to carry
the increased magnetic flux of the high
powered instruments now in common use in
radio-telephony. It will be noted that the
margin of the armature 12 is free from con-
95 tact with the upper edge of the cup 3, and
it is what may be termed a floating arma-
ture. In some cases, it may be made of con-
siderably smaller diameter, so that its mar-
gin will come well within the top of the 100
receiver cup. The cup 3 is screwed into the
ring 5, and adjusted to bring the poles of
the magnet 4 in proper relation to the under
face of the armature, or to the point where
the greatest vibration of the diaphragm and 105
armature will not cause contact with the
magnet poles.

The circuit leads 13 from the receiver cup
are carried out through the aperture 14 in
the margin of the base 1, and connected to 110
the receiving set in the usual manner.

As thus far described, it will be noted that

the diaphragm 10 and its armature 12 are entirely independent and out of contact with the receiver cup 3, and that the armature may be made of such thickness and diameter 5 as to carry a flux of much greater density from the magnet system without in any way impairing the flexibility or elasticity of the diaphragm, as would be the case if the diaphragm were used as an armature and 10 correspondingly thickened to carry such excessive magnetic flux as is now so common.

In Figs. 2, 5 and 6, is shown a slight modification of the device. In this case, the cap 2 and ring 5 are the same as above described. 15 The diaphragm 10' and armature 12' are connected by the coupling rivet 11'. The receiver cup 3' has at its upper margin a small annular cusp 16 upon which the margin of the armature 12' rests, so that when in place 20 the diaphragm bears upon the gasket 8, against which it is held by the armature 12' through the coupling rivet 11'. The armature 12' is provided with a series of apertures 17 annularly arranged, as shown, so as 25 to weaken the armature between its center and circumference, and thereby increase its flexibility.

Many non-metallic substances are well adapted for use as diaphragms in sound receiving or reproducing devices; among these 30 may be mentioned the following: mica, celluloid, parchment, parchment paper, glass, insulating fiber, vulcanized rubber, etc.

The use of the armature as above described, enables use to be made of any of these 35 substances, for it must be understood that the armature serves only as an armature and not as a sound reproducer, its vibrations due to the undulating magnetic flux from the magnet 40 being transmitted to the true sound diaphragm.

The structure as described also enables the use of diaphragms of very much larger 45 diameter, and consequently of correspondingly increased vibrational amplitude. In each of the forms shown, the armature may be termed a floating armature, the first form properly so, and the second form because of the fact that the armature proper may 50 be considered as that portion of the disk 12' that is within the ring of apertures 17, and the connecting bridges between adjacent apertures are merely weakened supports for the structure and to keep the armature in 55 place.

Minor changes coming within the spirit and scope of the invention are contemplated in the claims hereto appended, and said 60 claims are intended to broadly cover a receiver wherein the sound reproducing diaphragm is actuated by a floating armature connected thereto at its center.

Another advantage for the device may be mentioned, in that the movements of the armature are communicated to the diaphragm at its center, and not as is the case with the armature-diaphragm, where the magnetic pull is spread over a surface equal to that included between the magnet poles. The resulting tones coming from a diaphragm actuated from its center are found to be much clearer in tone, and without the muffled sounds so frequently heard in radio- 70 telephones.

I claim:

1. In a loud speaking telephone receiver, the combination of a receiver cap, a non-metallic diaphragm within said cap, a floating armature secured in spaced relation to the center of said diaphragm, a screw threaded ring to clamp said diaphragm in the cap and a receiver cup having a magnet system and being adjustably secured to said ring whereby its magnet system may be adjustably spaced from said armature.

2. In a loud speaking telephone receiver, the combination of a receiver cap, a supporting base to which said cap is rigidly secured, an extension ring detachably secured within said cap, a diaphragm located within said cap, an armature spaced from and centrally secured to said diaphragm, and a receiver cup and magnet system adjustably screw threaded within said ring with the poles of said magnet system spaced 95 from said armature.

3. In a loud speaking telephone receiver, the combination of a receiver cap, a supporting base therefor, an extension ring detachably secured within said cap, a diaphragm located within and spaced away from said cap, a floating armature centrally secured to and spaced from said diaphragm, a receiver cup and its magnet system, and means for adjustably securing said cup within said ring with the poles of its magnet system adjustably spaced away from the face of said floating armature.

4. A loud speaking telephone receiver comprising a receiver cup, a cap fitted thereto, said cap having an annular recess, a pair of gaskets disposed in the recess, a disc diaphragm held at its edges between said gaskets, a ring screw-threaded into the recess to clamp said gaskets and diaphragm in firm engagement in said cap, a metallic armature disc rigidly held in spaced relation from said diaphragm, a single axial connection between said diaphragm and armature, said armature being otherwise unconfined, a pair of magnets, and a cup in which said magnets are fixed, said magnet cup being adjustably screw-threaded into said clamp ring.

EARL H. ROLLINSON.
